UNITED STATES PATENT OFFICE

166,484

COMBINATION TOY CHAIR, CRADLE, AND TABLE

Charles A. Nash, Seattle, Wash.

Application December 8, 1950, Serial No. 13,333

Term of patent 14 years

(Cl. D15—1)

To all whom it may concern:

Be it known that I, Charles A. Nash, a citizen of the United States, residing at Seattle, State of Washington, have invented a new, original, and ornamental Design for a Combination Toy Chair, Cradle and Table, of which the following is a specification, reference being had to the accompanying drawing, forming a part hereof;

Figure 1 is a perspective view of a combination toy chair, cradle and table, showing my new design as it appears when used as a chair;

Figure 2 is a perspective view thereof as it appears when used as a cradle;

Figure 3 is a perspective view thereof as it appears when used as a table.

I claim:

The ornamental design for a combination toy chair, cradle and table, as shown.

CHARLES A. NASH.
